UNITED STATES PATENT OFFICE.

FRANK ALLEN, OF NEW YORK, N. Y.

DESIGN FOR A NECKTIE.

SPECIFICATION forming part of Design No. 25,658, dated June 23, 1896.

Application filed March 26, 1896. Serial No. 585,015. Term of patent 14 years.

To all whom it may concern:

Be it known that I, FRANK ALLEN, a citizen of the United States, residing at New York, in the county and State of New York, have invented and produced a new and original Design for Neckties, of which the following is a specification.

This design relates to neckties; and the leading feature of the design consists in a necktie-bow having fields at its end portions provided with longitudinal stripes, a star-field at one extremity, and a central field having stripes extending transversely to the longitudinal stripes of the end fields.

15 The design is illustrated by the accompanying drawing, in which the figure is a face view of my design for a necktie-bow.

In the drawing it will be observed that the bow is in the form of a bow-knot, and is provided with end fields 1, having longitudinal stripes 4. One of the end fields is provided at its extremity with a field 3, having stars 6.

A field 2 is arranged centrally between the ends of the bow and is provided with stripes 5, extending transversely to the longitudinal stripes 4 of the end fields 1. The field 2 is shown provided with a medallion or picture 7. The bow is also shown as provided with a band 8.

The design provides an ornamental and 30 handsome necktie-bow, which presents a distinguishing and characteristic appearance to the eye.

What I claim is—

The design for a necktie-bow, substantially 35 as shown and described.

In testimony whereof I have hereunto set my hand in the presence of two subscribing witnesses.

FRANK ALLEN.
